SEED PLACEMENT TUBE FOR AGRICULTURAL PLANTERS

Donald E. Williams, Garden City, Kans., assignor to
Agra-Plant, Inc., Newton, Kans.

Filed Mar. 25, 1971, Ser. No. 128,216

Term of patent 14 years

Int. Cl. D8—01

U.S. Cl. D35—2

FIG. 1 is a side elevational view of the seed placement tube for agricultural planters, embodying my present design;

FIG. 2 is a top plan view thereof;

FIG. 3 is a view showing one end thereof;

FIG. 4 is a bottom view; and

FIG. 5 is an elevational view showing the opposite end thereof.

I claim:

The ornamental design for a seed placement tube for agricultural planters, as shown.
